UNITED STATES PATENT OFFICE.

JONAS J. BYBERG, OF SILVERTON, OREGON.

WALNUT SCRUBBER.

Application filed September 21, 1926. Serial No. 136,877.

This invention relates to devices for scrubbing and cleaning nuts and the general object of the invention is to provide a device of this character which is very simple, which will not take much power to operate, and particularly which will thoroughly scrub and clean walnuts or other nuts.

A further object is to provide a machine of this character which, for the purpose of scrubbing nuts, utilizes two opposed and relatively movable scrubbing mats of cocoa fiber which can be quickly, easily and cheaply replaced after they have been worn out.

Another object is to provide means whereby these cocoa fiber scrubbing mats may be resiliently forced toward each other and adjusted to suit nuts of different diameters or to secure a greater or less frictional contact with the surfaces of the nuts.

Other objects will appear in the course of the following description.

My invention is illustrated in the accompanying drawings wherein:—

Figure 1 is a side elevation of a nut scrubbing machine constructed in accordance with my invention;

Fig. 2 is a fragmentary transverse section on the line 2—2 of Figure 1;

Fig. 3 is an end elevation of the scrubbing machine;

Fig. 4 is a section on the line 4—4 of Figure 1;

Fig. 5 is a detailed fragmentary section of one of the scrubbers on the line 5—5 of Figure 1.

Referring to these drawings it will be seen that my machine embodies a hopper 10 mounted upon corner posts 11, these corner posts being connected by braces 12, carrying the intermediate vertical members 13, these vertical members supporting a crank shaft 14. This crank shaft carries oppositely disposed cranks 15 on its ends and the intermediate friction drive wheel or belt wheel 16.

The hopper has a relatively long and narrow discharge mouth and disposed below this mouth and extending parallel to the side walls thereof are the opposed scrubbing elements consisting of the two cocoa fiber mats 17 and 18 which are arranged parallel to each other and having their fibers or bristles projecting inward toward each other, there being just space enough between the inner surfaces of these scrubbing mats to receive the nuts from the hopper.

The mats proper may be supported by means of exterior plates 19 or in any other suitable manner and as illustrated, these plates 19 carry projecting ears 20 constituting bearings and through which pass the longitudinally extending rods 21, upon which the bearings 20 are adapted to slide. These plates or walls 19 are respectively connected by crank rods 22 to the cranks 15 and thus the opposed mats may be caused to reciprocate in opposite directions. One of the mats might be fixed and the other one reciprocate but I prefer that both mats reciprocate.

The ends of the rods 21 are engaged in openings or sockets 23 formed in the members 13. It is desirable that the scrubbing elements be urged toward each other or that the scrubbing elements shall be adjustable to control the distance between the elements. This might be secured by means of adjustment screws but preferably by springs. Thus, as illustrated in the drawings, the brushes are urged toward each other by spring pressure upon the rods 21. These rods are illustrated as being connected at their ends by bolts 24 engaged with one of said rods and extending loosely through the other rod, the last named rod being mounted in slots formed in the braces 13 to permit the last named rod to shift. The spring 25 surrounds the outer end of the bolt and bears against a washer 26, which in turn bears against the adjacent rod 21 and the tension of this spring 25 may be adjusted by means of the nut 27 operating on the screw-threaded portion of the bolt 24. (There may be as many of these bolts 24 as it may be found necessary.)

Below the scrubbing elements there is disposed a transversely extending downwardly inclined grate 28 supported on suitable frame bars 29 and below this grate there is a water trough or chute 30. Disposed above the hopper is a spray pipe 31 perforated to discharge water downward on the nuts contained in the hopper. The operation of the mechanism is as follows: The walnuts or other nuts or even vegetables to be cleaned are placed within the hopper and a spray of water is directed over them, unless it be desired to scrub them in a dry state, which water causes them to be thoroughly soaked before passing down between the two scrubbing elements. As the nuts pass downward between the scrubbing elements they are

given a rolling action due to the relative movement of the brushes or scrubbing elements. This rolling action causes the brush fibers to enter the crevices of the nuts, thus removing all embedded dirt, fiber and loose hulls that may be clinging to the nut. The water from the spray passes down around the walnuts and between the scrubbing devices and rinses the dirt as it is loosened by the scrubbing action of the brushes.

The walnuts gradually descend because of their weight and the downward flow of water. As their speed of descent depends on the pressure of the brushes against the nuts the time taken for scrubbing can be controlled by controlling the pressure of the fiber mats upon the walnuts by properly tensioning the springs 25. Preferably a finger 32 will be attached to one of the scrubbing elements at the upper edge thereof and will extend up into the mouth of the hopper so as to act as an agitator preventing the walnuts from clogging within the hopper. When the walnuts have passed downward between the brushes they are separated from the water and then by means of the grate or screen 28, the walnuts rolling down the screen are discharged into any suitable container. The dirt and water will be caught in the trough 30. Obviously if running water is not available to supply the machine a tank can be substituted for the trough 30 and the water pumped up from this tank and discharged into the hopper. It is not absolutely necessary to have both brushes reciprocate as one of the brushes might be stationary and the other brush only reciprocate, but poorer scrubbing will result.

One of the objects of this machine is that the brushes or scrubbing elements are self-cleaning because they stand on edge and, therefore, no dirt can collect between the

fibers. Obviously the machine may be run by hand if desired instead of by power.

While I have illustrated a particular embodiment of my invention I do not wish to be limited thereto as the arrangement of parts and details of construction might be varied in many ways without departing from the spirit of the invention as defined in the appended claims.

While this machine is particularly designed for scrubbing and cleaning nuts, it may also be used for cleaning vegetables such as turnips, potatoes, and the like.

I claim:

1. A scrubbing machine comprising two confronting vertically disposed scrubbing elements, means for relatively reciprocating said elements in opposite directions, a hopper discharging into the space between said elements, means for adjusting the distance between the inner faces of said elements, and means for yieldingly holding said elements in adjusted position and resiliently urging the elements toward each other, said means being adjustable.

2. A scrubber of the character described comprising a supporting frame, a hopper mounted thereon and having an elongated discharge opening, opposed relatively flat scrubbing elements disposed in confronting relation positioned below the hopper and having inwardly projecting fibers, longitudinally extending rods upon which said scrubbing elements are mounted for reciprocation, means for adjusting the rods toward or from each other and yieldingly urging the rods on one side toward the rods on the other, means for reciprocating the scrubbing elements on the rods.

In testimony whereof I hereunto affix my signature.

JONAS J. BYBERG.
